Primary Examiner — Brett Miller(74) *Attorney, Agent, or Firm* — CANTOR COLBURN LLP(57) **CLAIM**

The ornamental design for a barbecue oven, as shown and described.

DESCRIPTION

FIG. 1 is a top, front, left side perspective view of a barbecue oven;

FIG. 2 is a bottom, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarge view of a rocker in FIG. 1.

The broken lines in the figures depict portions of the barbecue oven that form no part of the claimed design.

1 Claim, 9 Drawing Sheets(56)
